METHOD OF SPRAYING LIQUID MATERIALS

Hermann Wentzel, Berlin, Germany, assignor to
 Sauerstoff-Central fur Medizinische Zwecke, Dr.
 Ernst Silten, a firm of Germany

Application April 24, 1933, Serial No. 667,566
 In Germany June 22, 1932

4 Claims. (Cl. 299—95)

This invention relates to the atomization of liquids, for various purposes.

More particularly it relates to a method of and an apparatus for spraying or bringing of fusible or liquid materials on surfaces, for example, on the human body and in body openings.

In order to bring molten, wax-like materials, such as paraffin, on the human body for therapeutic or cosmetic use, there had been proposed 10 an apparatus in which the material was fused and then sprayed either under the pressure of compressed gas, usually compressed air, or by a stream of gas or air by means of a nozzle. This type of apparatus was costly and complicated due 15 to the necessity for providing compressors, fans, pressure cylinders and the like, and by reason thereof it was unhandy and difficult to handle.

The present invention is intended and adapted to obviate the disadvantages of the prior art and 20 it is among the objects thereof to provide an apparatus which is simple, cheap and easy to handle.

In one aspect, the invention comprises a method and an apparatus in which the liquid material 25 may be sprayed without the use of streams of gases under pressure. If solid or liquid paraffin or similar fusible substances are used, there is mixed therewith readily volatile substances or such substances as will, under the conditions of 30 operation, generate gases or vapors. The mixture is placed in the apparatus and heated under such conditions as to melt the paraffin and produce gases or vapors, which exert sufficient pressure 35 on the liquid paraffin to cause spraying or atomization thereof upon the opening of a suitable valve in the apparatus.

In a variation of the invention the solid or liquid material is placed in the apparatus which is provided with an additional chamber containing a 40 substance or mixture of substances capable of generating gases or vapors upon being heated. Such gases or vapors may be generated by the vaporization of the substances, by a chemical reaction between the ingredients, or in any other 45 manner. These gases and vapors exert the pressure necessary for causing spraying of the liquid material. A single heating means may be used to fuse the paraffin and to generate the gases.

The invention is applicable for other uses as, 50 for example, for the atomization of liquids for dental purposes or for the generation of gases for medicinal, therapeutic and hygienic purposes.

In practicing the invention, paraffin may be mixed with low boiling substances such as pentane, hexane, chloroform, carbon tetrochloride 55

and the like at a low temperature, or said substances may be placed in a separate chamber communicating with the paraffin chamber. Upon heating of the paraffin to the temperature at which it is to be sprayed, the paraffin melts and 5 the substances are vaporized, generating the necessary pressure in the apparatus. In place of vaporizable substances there may be used substances which at elevated temperatures liberate 10 gases, such as sodium bicarbonate which evolves carbon dioxide. Mixtures of sodium bicarbonate with solid organic acids or inorganic acids or organic salts, such as bisulphites, bisulphates, acid tartrates, or solutions of salts which generate 15 gases, such as a concentrated solution of sodium nitrite and ammonium chloride which evolves nitrogen, may be used. There may be used formed bodies, such as briquets of substances which under the influence of heat decompose and evolve 20 gases. These and other methods, well-known to those skilled in the art may be used to provide the necessary gas pressure in the apparatus.

In the accompanying drawing constituting a part hereof, the single figure is a vertical cross- 25 sectional view of one form of apparatus adapted for the practice of this invention.

There is provided a container 1 of any suitable material having a filling opening 2 closed by cap 3. A cover 4 having a sealing washer 5 is adapted 30 to be held in place by bolts 6. A thermometer 7, pressure gauge 8 and pressure relief valve 9 are held in cover 4. At the lower portion of container 1 is a tube 10 having a valve 11 therein and terminating in nozzle 12.

Within container 1 is a tube 13, the lower end 14 of which is closed and the upper end is provided with an opening 15 communicating with the vapor space of container 1. A depending skirt 16 on cover 2 serves to hold tube 13 in place. 40 A container 17 fitting into tube 13 has a handle 18 whereby it may be inserted into and removed from tube 13, and a cap 19 closes the opening in cover 2. Circular electric heating element 20 surrounds tube 13 and serves to heat the containers 1 and 13, and lead-in wires 21 and 22 serve as a means for connecting said element to a suitable source of electrical energy.

The following are a number of examples of the 5 practice of this invention:

Example 1

A mixture is made of molten paraffin having a melting point of 42° C. with 3% of its weight of carbon tetrachloride, and the mixture is allowed 5

to cool. It is placed in the container 1 through the top and the cover 4 is secured thereto. Electric current is caused to flow through heating element 20 to raise the temperature of the paraffin 5 above 77° C., which vaporizes the carbon tetrachloride, the vapors rising to the upper part of the vessel above the liquid level 23 and exerting pressure on the liquid. The valve 11 is opened and by reason of the pressure, paraffin is sprayed 10 out through nozzle 12.

Example 2

Liquid paraffin is placed in the container 1 through the opening 2 to the level 23. In the inner container 17 there is placed a mixture of sodium bicarbonate and sodium bisulphate, and the caps 3 and 18 are set in place. The apparatus is heated by means of heating element 20 to the desired temperature for spraying. The heat 15 causes a reaction to take place in container 17 between the substances therein generating carbon dioxide and water vapor in accordance with the following equation:

The gas and vapor rise to the top of the inner cylinder 18 and out through opening 15 into the space in container 1 above the liquid level 23. The desired pressure of several atmospheres may 20 be built up in this manner and the safety valve 9 prevents too high a pressure from forming. Upon opening the valve 11, the paraffin is caused to flow through nozzle 12 and be atomized.

Example 3

The apparatus may be filled with liquid paraffin through opening 2 and a briquet consisting essentially of potassium chlorate, catalysts, and oxidizable substances such as iron powder, is placed in inner container 17, and is ignited. Container 17 is slipped into the apparatus and the caps 3 and 18 screwed in place. The briquet burns slowly and generates oxygen, providing pressure for spraying as in Example 2. In the present case it is unnecessary to use the heating element 20 because the briquet not only generates the pressure gas but also gives off sufficient heat to liquefy and heat the paraffin to the proper temperature for spraying. The apparatus in this case need not have an electrical heating element and it may be omitted.

Although the invention has been described setting forth several examples of the operation thereof, and describing a single form of apparatus, these examples are to be considered as setting forth a few of the many possible variations as will be apparent to those skilled in the art. For example, the thermometer 7, pressure gauge 8, safety valve 9 may be omitted. In some cases the heating element 20 or the inner container 17

may be omitted as explained above. The form of the apparatus may be varied to suit the convenience and the apparatus may be applied to other uses. For instance, when gases such as carbon dioxide, oxygen, nitrous oxide or mixtures thereof are generated, they may be used outside of the apparatus for the atomization of liquids. They may also be used for inhalation, narcosis, and the like. In such case the nozzle 12 and valve 11 would be replaced by a rubber tube. These 10 and other changes may be made in the present invention within the scope thereof, and the invention is not to be limited except by the claims appended hereto.

What I claim is:

1. A method of spraying which comprises providing a container, placing therein a sprayable fusible material, placing therein a different substance capable of generating aeriform fluid when subjected to heat, sealing said container, heating 20 said container sufficiently to generate aeriform fluid, fusing said material and causing said material to pass out of the container under the pressure so generated substantially free from said aeriform fluid.

2. A method of spraying which comprises providing a container, placing therein a sprayable fusible material, placing therein a different substance capable of generating aeriform fluid when subjected to heat, sealing said container, heating 30 said container sufficiently to generate aeriform fluid by chemical reaction of said different substances, fusing said material and causing said material to pass out of the container under the pressure so generated substantially free from said aeriform fluid.

3. A method of spraying which comprises providing a container, placing therein a sprayable fusible material, placing therein a different substance capable of generating aeriform fluid when 40 subjected to heat, sealing said container, heating said container sufficiently to generate aeriform fluid by combustion of said different substance, fusing said material and causing said material to pass out of the container under the pressure 45 so generated substantially free from said aeriform fluid.

4. A method of spraying which comprises providing a container, placing therein a sprayable fusible material, placing therein a different substance capable of generating aeriform fluid when subjected to heat, sealing said container, heating 50 said container sufficiently to generate aeriform fluid by vaporization of said different substance, fusing said material and causing said material to 55 pass out of the container under the pressure so generated substantially free from said aeriform fluid.

HERMANN WENTZEL.
